C. B. GREGORY, OF BEVERLY, NEW JERSEY.

Letters Patent No. 89,986, dated May 11, 1869.

IMPROVEMENT IN FURNACES FOR STEAM AND OTHER ENGINEERY.

The Schedule referred to in these Letters Patent and making part of the same.

To all whom it may concern:

Be it known that I, C. B. GREGORY, of Beverly, county of Burlington, and State of New Jersey, have invented an Improved Furnace, or Fire-Place; and I do hereby declare the following to be a full, clear, and exact description of the same.

My invention consists of certain improvements, fully described hereafter, in the fire-place for which Letters Patent were granted to me on the 3d day of March, A. D. 1868.

In order to enable others skilled in the art to make and apply my invention, I will now proceed to describe its construction and operation, reference being had to the accompanying drawing, which forms a part of this specification, and in which—

Figure 1 is a transverse sectional view of my improved furnace, or fire-place;

Figure 2, a longitudinal section, on the line 1—2, fig. 1;

Figure 3, a sectional plan view, on the line 3—4, fig. 1;

Figure 4, a plan view;

Figure 5, a sectional perspective view of part of one side of the furnace;

Figure 6, a transverse section of the furnace, showing a different arrangement of fire-brick;

Figure 7, a longitudinal section on the line 5—6, fig. 6;

Figure 8, a perspective view of one side of the fire-brick wall of the furnace; and

Figure 9, a view of part of my invention, as applied to a cylindrical fire-pot.

Similar letters refer to similar parts throughout the several views.

Referring to figs. 1, 2, 3, 4, and 5—

A is the front wall,

B, the base,

C, the rear wall, and

D D, the side walls of the furnace.

The grate-bars *a* are of the usual construction, and rest upon bearers *a'*, at the opposite ends of the furnace; and in the front wall *A*, below the grate, is the usual opening and ash-door *b*, and above the grate an opening, covered by the fire-door *b'*, fig. 2.

Extending along both sides and the back of the furnace, on a level with the top of the grate-bars *a*, is a ledge, on which rest the fire-clay walls *F* *F* and *G* of the fire-place *c*.

In each of the side walls of the furnace, beneath the fire-clay walls *F*, is a longitudinal channel, *e*, to which air is supplied through an opening or openings in the front wall *A*; and each of these channels communicates with a narrow passage, or chamber, *f*, which intervenes between the fire-clay walls and side walls *D*.

The walls *F* are built up of fire-bricks *g*, bevelled on their inner and upper edges, so as to form grooves *h*, as best observed in fig. 5, for a purpose described hereafter; and in the cement between the bricks is a number of small openings, *i*, which form a communication between the chambers *f f* and interior of the fire-place *c*.

A valve, or door, *j*, is hinged to each of the side walls

of the furnace, in such a position that it shall rest upon the top of the adjacent wall *F*, and thus close the upper end of the chamber *f*. (See fig. 5.)

Extending around the top of the furnace is a plate, *H*, between which and each of the walls *F* is a narrow passage *k*, and beneath this plate, and above each of the valves *J*, is a steam-pipe, *l*, directed toward the centre of the fire-place.

The steam-pipe *l* has two branches, *m m*, which communicate with the channels *e*, or with the spaces above these channels, at the rear of the fire-brick walls. (See figs. 2 and 3.)

When a fire is ignited on the grate-bars *a*, cold air enters the channels *e*, and steam is forced through the branch-pipes *m*, a film of combined steam and air passing upward into each of the narrow chambers *f*, and thence through the perforations *i* of the fire-clay walls, in a condition best adapted to aid in the combustion of the gases which rise from the burning fuel.

At the same time, jets of steam are projected from the nozzles *l'* into the fire-place; and as these nozzles are arranged at points opposite, or nearly opposite to each other, as best observed in fig. 4, the jets, meeting in the centre, will cause an agitation and thorough mixing of the gases with the air and steam, and insure their rapid and complete combustion.

In forcing the jets of steam from the nozzles *l'*, a partial vacuum will be produced in the spaces *k* beneath the plate *H*, which will cause the valve *j* to rise slightly, and admit an additional supply of air, or air and steam, from the chambers *f* into the fire-place.

In figs. 6, 7, and 8, is shown a somewhat different construction of fire-clay walls, the chambers *f f* being dispensed with, and the air, or air and steam from the channels *e*, caused to travel through longitudinal and vertical grooves *r*, formed on the rear sides of the fire-clay walls. From these grooves the air passes through perforations *i*, or beneath the valves *j j*, into the fire-place, as in the first instance.

By the employment of these grooves, or channels *r*, the air, or combined air and steam is caused to travel, in a circuitous course, in much the same manner as when passed through a mass of gravel, or other similar granulated material, as described in my patent of March 3, 1868, and I have found by experiment, that the result obtained is the same, namely, a fire of intense and uniform heat.

It should be understood, however, that, although I have described the grooves *r* as being arranged at right angles to each other, and have so illustrated them in the drawing, they can be curved or arranged in any manner by which the air and steam may be caused to travel circuitously, and in small volumes, to the points where they have to be fed to the fire.

It should also be understood that I do not confine myself to forming these grooves in fire-clay only, as in some instances where there is to be a great number of grooves of different forms, and arranged at different

angles, cast-iron can be economically substituted for the fire-clay.

It will be evident that this arrangement of external grooves can also be advantageously applied to cylindrical fire-pots, as illustrated in fig. 9 of the drawing.

The principal objection to the employment of perforated fire-pots, or walls, has been the liability of the holes to become stopped, or choked, either by dust or by the vitrifying of the inner surfaces of the walls, when exposed to great heat.

These objections I have entirely overcome, by, in the first place, forcing steam through the perforations, and, secondly, by forming grooves *h* on the inner surfaces of the walls. The steam serves the twofold purpose of preventing the accumulation of dust in the perforations, and of preventing the destruction of the bricks by heat, while the grooves *h* break the continuity of the surfaces which are exposed to the fire, and prevent the running down of vitrified material, and consequent choking of the holes.

I am aware that jets of steam have been before introduced into furnaces, to aid combustion, but these jets are generally so directed as to drive the gases to-

ward the chimney, before they have been thoroughly consumed. This objection is obviated in my invention, by so arranging the nozzles *l*, (whatever may be their angle,) that their jets shall be directed toward each other, and toward the centre of the fire-place.

I claim as my invention, and desire to secure by Letters Patent—

1. The arrangement of channels and perforations in the walls of a fire-place, substantially as described.

2. The arrangement, substantially as described, of steam-pipes and nozzles, by which jets of steam are directed on to the fire, in the course described, for the purpose specified.

3. In combination with the subject-matter of the second claim, the valves *j* above the air-passages, for the purpose described.

In testimony whereof, I have signed my name to this specification, in the presence of two subscribing witnesses.

C. B. GREGORY.
